United States Patent Office

Des. 186,618
Patented Nov. 10, 1959

186,618

LAMP

Jack W. Haywood, Los Angeles, Calif., assignor to Modeline Company of California Inc., Los Angeles,
Calif., a corporation of California

Application June 10, 1959, Serial No. 56,291

Term of patent 14 years

(Cl. D48—20)

Fig. 1 is a perspective view of a lamp, showing my new design;

Fig. 2 is a section taken on line 2—2 of Fig. 1; and
Fig. 3 is an enlarged section taken on line 3—3 of Fig. 2.

The dominant features of my design reside in the portions shown in full lines.

I claim:

The ornamental design for a lamp as shown and described.
